UNITED STATES PATENT OFFICE.

MILTON B. REACH, OF CHICOOPEE, MASSACHUSETTS, ASSIGNOR TO A. G. SPALDING & BROS. MANF'G. CO., A CORPORATION OF MASSACHUSETTS.

DESIGN FOR A HEEL-CLAMP FOR SKATES.

45,311.

Specification for Design.

Patented Feb. 24, 1914.

Application filed July 30, 1913. Serial No. 782,136. Term of patent 14 years.

To all whom it may concern:

Be it known that I, MILTON B. REACH, a citizen of the United States, residing at Chicopee, in the Commonwealth of Massachusetts, have invented a new, original, and ornamental Design for a Heel-Clamp for Skates, of which the following is a specification, reference being had to the accompanying drawing, forming part thereof.

The design is shown in the accompanying drawing, in which—

Figure 1 is a side view of the clamp. Fig. 2 is a view of the heel clamp looking from the front; Fig. 3 is a plan view of the heel clamp.

I claim:

The ornamental design for a heel clamp for skates as herein shown.

MILTON B. REACH.
